UNITED STATES PATENT OFFICE.

JOHN H. FELMLEE, OF ALLEGHENY, PENNSYLVANIA.

TENONING-MACHINE.

SPECIFICATION forming part of Letters Patent No. 437,414, dated September 30, 1890.

Application filed October 25, 1889. Serial No. 328,209. (No model.)

To all whom it may concern:

Be it known that I, JOHN H. FELMLEE, of Allegheny, Pennsylvania, have invented a new and useful Improvement in Tenoning-
5 Machines, which improvement is fully set forth in the following specification, reference being had to the accompanying drawings.

Similar letters of reference indicate corresponding parts.

10 The object of my invention is a foot-power tenoning-machine, the construction of which will be fully set forth or described hereinafter.

In the accompanying drawings, Figure 1 is a top view of my tenoning-machine. Fig. 2 is a side view in elevation. Fig. 3 is a front end view. Fig. 4 is a top sectional view of the sliding head, and Fig. 5 is an edge and top view of the knife or bit.

15 A represents the bar on which the head D slides or operates.

B B represent slotted standards bolted to the base-plank V. The standards have slots a a, and through these slots a a the bolts a' a' move up and down, thus raising or lowering 20 the bar A to suit the thickness of the wood to be worked.

C C is the frame-work of the sliding frame. E is the bit, which is screwed to the head D.

25 F represents a small saw, which is secured to the head D at the opposite side of the bit. This little saw is intended to cut the shoulder in front of the bit and it will be set accordingly. The movement of this saw F across the wood that is being worked will be 30 simultaneous with the bit, as both are fastened to the same moving head or slide.

G is the screw that raises and lowers the head D in the frame C.

H is a bumper or stop adjustable on the 35 bar A, and is fastened in place by a set-screw h. At the top of this bumper is an extension integral therewith, in which is a threaded opening for the feed-screw M. This feed-screw M is to regulate the feed of the bit, as 40 will be more fully explained hereinafter.

N is the feed-bar, to which is secured the ratchet-teeth L at the end K. This feed-bar N and the said ratchet-teeth are intended to 45 operate the feed-wheel I, which is fixed on the feed-screw G.

O is a slide-bar on the standards B'. On this bar O the slide P operates. Through

this slide O is a screw P', to which is attached the shoe P. This is to hold the wood steady when being worked.

55 R is a rope, which is secured to the cutter-head D at r² at one end, then running over the sheave W in the standard B, then over the sheave W' in the treadle, and then secured at r.

r³ is a rope secured at r' at one end, and from thence extends over the sheave Q.

X is a spring-coil shaped on a bar, at one end of which bar is the sheave Q, and at the other end is a band X', which holds the end 65 of the coil firmly on the bar. This coil-spring is made of spring-steel wire of adequate strength and power for the purpose used.

S is the treadle and is pivoted to the timber S'.

70 T represents a gib.

U represents a guard pivoted at u to the base-plank, and is suitably slotted and with a set-screw is adjustable to any desired angle.

I do not confine myself to any special kind 75 of knife—such as the knife E—for my machine will work with many other kinds or sizes of knives.

When the operator presses down on the 80 treadle S, the rope R pulls over the sheave W and draws forward the head D, carrying the bit E and saw F, the latter cutting the shoulder of the wood and the former or bit cutting out or shaving the same. In this movement the bar N, which carries the ratchet-teeth L, 85 is carried forward and its end comes in contact with a bumper on the bar A, which drives the ratchet back, when it is ready for a second movement. The return of the head A for a second cut is effected by the power of 90 the coiled spring X, sheave Q, and rope r³. On this return movement the other end of the bar N comes in contact with the end of the screw M of the bumper H, and this drives the ratchet L again along the feed-wheel I over 95 the teeth of the same, thus causing the feed-screw G to revolve. This movement lowers the knife a sufficient distance for another shave or cut, and thus this movement is kept up, the bar N alternately thrown back and 100 forward, and at each forward move the wheel I is made to move the distance required. The screw M is made adjustable, so as to give the bar N a long or short stroke or movement.

It will readily be seen that a short stroke will make a shallower cut than a much longer one will make. By reversing the movement of this screw G the knife or bit may be raised 5 and made ready for new work. This raising of the bit is effected by means of the crank at the upper end of the screw G.

Having thus described my invention, what I claim, and desire to secure by Letters Patent of the United States, is—

1. In a tenoning-machine, the combination of the standards mounted upon a suitable frame, the bar A, secured thereto, a frame C, applied to the bar and having an endwise 15 movement thereon, and the vertically-adjustable head connected to the frame C so as to move therewith and having a cutting-tool secured to its lower end, substantially as shown.
2. In a tenoning-machine, the combination of a suitable supporting-frame, standards secured thereto, a supporting-bar adjustably secured to the standards, the endwise-moving frame applied to the bar, and a mechanism 25 for moving it thereon, the vertically-adjustable head mounted on and movable with the frame and having a cutting-tool secured to its lower end, and a mechanism for returning the frame and head to position, substantially 30 as described.
3. The combination of the supporting-bar and its supporting-standards with the endwise-moving frame placed upon the bar, the vertically-adjustable head placed on the 35 frame, a mechanism for moving the head and frame endwise, a mechanism for returning them to position, and a stop placed on the bar to limit their return motion, substantially as set forth.
4. The combination of the standards, the supporting-bar secured thereto, the movable frame placed on the bar, the vertically-adjustable head connected to the frame, a stop placed on the bar and provided with the adjusting-screw M, and suitable mechanisms 45 for moving the frame and head back and forth on the bar, substantially as specified.

5. In a tenoning-machine, the combination of the main frame, the supporting-bar, the sliding frame placed thereon, the head placed 50 upon and moving with the frame, a pulley at one end of the main frame, a treadle below the main frame carrying a pulley, and a rope having one end secured to the sliding frame passing around the said pulleys and its opposite end secured to the main frame, substantially as shown.

6. The combination of the supporting-bar, the sliding frame placed thereon, the vertically-adjustable head, and the mechanisms for 60 moving the frame and the head back and forth on the bar, with the supporting-bar placed parallel with the one A and the vertically-adjustable clamp placed thereon, substantially as described.

7. The combination of the supporting-bar, the sliding frame placed thereon, the vertically-adjustable head, the rope R, pulleys W W', and the treadle with the rope r³, and the spring-actuated pulley Q, substantially as set 70 forth.

8. In a tenoning-machine, the combination of the head, the screw passing vertically through it, the ratchet-wheel on the screw, the ratchet-bar for operating the wheel, and 75 the feed-bar to which the ratchet-bar is connected, substantially as specified.

9. The combination of the head having a screw-thread in its upper end, the screw passing vertically through it, the ratchet-wheel 80 on the screw, the ratchet-rod, the feed-rod to which the ratchet-rod is attached, and the stops against which the ends of the feed-rod strike, substantially as shown.

In testimony that I claim the foregoing as 85 my invention I hereto set my hand in presence of two witnesses.

JOHN H. FELMLEE.
